UNITED STATES PATENT OFFICE.

JOSEPH MARION KING, OF JACKSONVILLE, FLORIDA.

FLUID-TRACTOR.

1,125,341.

Specification of Letters Patent.

Patented Jan. 19, 1915.

Application filed July 31, 1912. Serial No. 712,468.

To all whom it may concern:

Be it known that I, JOSEPH MARION KING, a citizen of the United States, residing at Jacksonville, in the county of Duval and 5 State of Florida, have invented certain new and useful Improvements in Fluid-Tractors, of which the following is a specification, reference being had therein to the accompanying drawings.

10 This invention provides a device that utilizes steam, the gaseous products of combustion, or other fluids entering the device under pressure, as its motive medium, and it particularly is adapted for use in association with exhaust-conduits of internal- 15 combustion engines.

Some of the principles of fluid action involved in this device are similar to those involved in my copending application for 20 patent on fluid-tractor, filed April 27, 1912, Serial Number 693,566, and in addition the inductive action characteristic of some forms of ejectors and a vacuum-chamber contributing to production of a substantially continuous flow of liquid are employed.

Among the objects of the invention is to provide a device that, by employment of energy present in exhaust or other fluids 30 initially under pressure, will cause a flow of liquid, as engine circulating-water or bilge-water, and that will increase the efficiency of an engine with which it is associated.

The device is so formed and arranged that 35 momentary subsidences of pressure or partial vacuums are caused by intermittent expulsion of the motive medium through the device, and these lapses of pressure are utilized to cause a flow of liquid.

40 When read in connection with the description herein, the details of construction and arrangement of parts will be apparent from the accompanying drawings, forming part hereof, wherein an embodiment of the invention is disclosed, for purposes of illustration.

While a preferred form of the invention is shown, it is to be understood that it is not the intention to be limited necessarily to 50 the precise delineation herein in interpretation of claims hereinafter, as it is obvious that parts can be variously formed and organized, without departing from the nature and spirit of the invention.

55 Like reference-characters refer to corre-

sponding parts in the views of the drawings, of which—

Figure 1 is a longitudinal sectional view; Fig. 2 is an end elevation, looking at the receiving-end; and Fig. 3 is an end elevation, 60 looking at the discharge-end.

Referring more particularly to the drawings, 5 designates an outer casing or shell, preferably circular in cross-section, having receiving and discharge ends 6 and 7 arranged for connection with parts of an exhaust-disposal means or other conduit. In the vicinity of the discharge end, the outer casing has an inwardly-extending annular flange or wall 8, on which is formed a valve-seat 9 arranged to have coöperate therewith to close the device against atmospheric pressure an outwardly-opening valve 10. The valve has thereon a stem 11, guided by a guideway in a frame 12, adjustably held in 75 an interiorly-threaded portion of the discharge end. Interposed between the frame and valve around the valve-stem are an outer coil-spring 13 and an inner coil-spring 14. The spring 13 may be of less strength or tension than spring 14, and it is in contact with the valve and operates to press the latter against its seat; and the spring 14, which may be of greater strength or tension, is shorter and has retarding effect on opening 80 movement of the valve only when the valve has opened somewhat from its seat. The springs also may be of like tension and the spring 14 still have an additional retarding action on the valve. The valve is opened 90 under the influence of exhaust or pressure impulses and closed under the influence of atmospheric pressure, as in the case of the similarly-located valve of the earlier application hereinbefore mentioned, and the inner spring operates to retard opening movement of the valve after the valve has opened a certain distance, so that that spring is compressed and the valve permitted to have further opening movement only under comparatively great pressures.

Connected to or integrally formed with the flange or wall 8 is an exhaust-conduit 15, preferably circular in cross-section, which extends longitudinally and centrally of the 105 device to the receiving end where it is joined to the outer casing, thereby constituting an exhaust-passage leading to the valve 10. There is a cooling-space 16 between the casing and conduit, which has a 110

liquid-inlet 17, preferably located in the lower portion of the device and in the vicinity of the discharge end. The valve 10, it will be seen, is located directly in the path 5 of fluids moving in the conduit. A secondary conduit 18, preferably circular in cross-section, is positioned centrally and longitudinally of the exhaust-conduit. It has a receiving end positioned in the vicinity of 10 the receiving end of the device and directly in the path of fluids entering that end, and it terminates in a discharge end somewhat removed from the valve 10 and positioned to discharge directly against that valve. 15 For a portion of its length intermediate its ends the secondary conduit is reduced in size, as shown at 18^a. The secondary conduit may be supported in the device in any suitable manner. In the present embodiment, it is supported by a circular wall 19 forming a passage 20 affording communication between the upper portion of the cooling-space and the secondary conduit near 20 its receiving end. 25 The mouth or entrance end of the secondary conduit has projecting thereinto a substantially funnel or truncated-cone shaped device 21, which is joined to the wall of the secondary conduit at its end, whereby it 30 receives all of the pressure fluids entering that conduit. From its entrance the member 21 reduces in size, so that it is smaller at its discharge end than at its receiving end, as a result of which there is an annular 35 space between it and the secondary conduit. Member 21 extends into the secondary conduit beyond the passage 20. The wall of the outer casing is deflected 40 outwardly to form a valve-chamber 22 over the passage 20, and communicating with this chamber is a vacuum-chamber 23 comprehended by a casing 24, removably held in place by having its screw-threaded lower part engaged with threads on the deflected 45 walls. The passage 20 has screw-threads removably holding a frame 25. This frame is formed with a seat 26 with which a valve 27 coöperates to close the passage, this valve being arranged to close against fluid pressure 50 in the secondary conduit and to open under oppositely-exerted influence. The valve has a stem 28 disposed in a guideway of the frame, and associated therewith is a spring 29 operating to close the valve. In 55 the present embodiment, the spring is disposed between the frame and a stop 30 on the stem. The parts are so relatively proportioned that, when the vacuum-chamber is removed from the device, the frame and 60 valve may be withdrawn. The vacuum-chamber is provided at or near the top with a pet-cock 31, in order that air may be admitted to the chamber and accumulations of liquid therein permitted to drain to the 65 cooling-space.

When the device is associated with an exhaust-conduit of an engine, and has its inlet 17 connected with a liquid-supply means, the actions therein are substantially as follows: Exhaust fluids enter the receiving end, and a portion of them flow through the secondary conduit and the remainder of them through the exhaust-passage exteriorly of the conduit. Under exhaust pressure the valve 10 opens and permits discharge of 70 fluids. The valve 27 prevents the exhaust fluids on their initial impulses into the device from passing into the cooling-space or reacting against liquid therein. After an exhaust, or a portion thereof, is impulsively 75 discharged from the device, there is a rebound or a tendency of the atmosphere to flow into the device. Back flow of air is prevented by the valve 10 closing against atmospheric pressure, and the engine thereby is relieved of the necessity of initially 80 overcoming atmospheric pressure or backlash on the next exhaust.

The hot exhaust fluids within the device sustain a reduction of volume due to the 85 cooling effects of the cooling-space. As a result of the tendency of gases to flow to restore stable equilibrium within the exhaust-conduit, the partial vacuums incident to reduction of fluid volume intermittently 90 occurring in the exhaust-conduit are effective not only initially to relieve the engine of the effect of atmospheric pressure on expulsion of an exhaust, but also to produce a "pull" of fluids therefrom, whereby the efficiency of the engine is increased; and the 95 partial vacuums also are effective on the fluids within the cooling-space. That is, there is a tendency of fluids to flow not only from the engine, but also from the cooling-space, and under this tendency the valve 27 opens and a flow of liquid induced from 100 that space. Further, there is an inductive effect on the liquid resulting from the disposition of member 21, which extends into 105 the secondary conduit beyond passage 20, as fluids impelled through this member have a drawing effect on fluids surrounding it, in accordance with well-known principles. Liquid entering through passage 20 becomes 110 commingled with fluids in the secondary conduit, and, also, in the exhaust-conduit between the end of the secondary conduit and the valve 10. This contributes to the 115 cooling of exhaust-fluids and liquefies the 120 water, or a portion of it, that is in the exhaust fluids in an attenuated or gaseous form, and there results a reduction of fluid volume in addition to that produced by the 125 cooled parts. Of course, the mixing of liquid from the cooling-space with exhaust fluids also has a cooling effect. The amount of reduction in volume due to liquefaction is apparent when it is considered that about three-sevenths of the product of combustion 130

of a mixture or air and gasoline or kindred fuels used in the operation of internal-combustion engines is water in a gaseous form. In the operation of the device as described, 5 water may be circulated through the cooling-space and drawn from the cooling-jacket of an engine, or from any other desired source as from the bilge of a boat for example.

10 When the flow of exhaust-fluids becomes so rapid as to exceed the motion of valve 10 acting against atmospheric pressure, the drawing and expulsion of liquid is continued by action of the fluids discharged from 15 member 21 into the secondary conduit. At high speed, the fluid flow is continuous, and both valves remain open, while with heavy-duty or slow-speed engines the flow of liquid occurs as a result of the intermittently- 20 occurring partial vacuums when the valve 10 is closed against atmospheric pressure. The vacuum-chamber 23 contributes to a uniform flow of liquid and prevents a tendency to rest inertia between exhaust impulses.

25 Having thus described my invention, what I claim as new, and desire to secure by Letters Patent, is—

1. A device of the kind described having therein an exhaust-passage, an exhaust-conduit 30 extending longitudinally of said passage and arranged to receive a portion of the pressure fluids entering the device, a liquid-supply passage leading into said conduit near its receiving end, and a valve arranged to permit liquid to enter said conduit through said passage and to prevent flow of fluids in the opposite direction.

2. A device of the kind described having therein an exhaust-passage, an exhaust-conduit 40 extending longitudinally of said passage and arranged to receive a portion of the pressure fluids entering the device, a liquid-supply passage leading into said conduit near its receiving end, a vacuum-chamber 45 in communication with said liquid-supply passage, and a valve arranged to permit liquid to enter said conduit through said passage and to prevent flow of fluids in the opposite direction.

50 3. A device of the kind described having therein an exhaust-passage, an exhaust-conduit extending longitudinally of said passage and arranged to receive a portion of pressure fluids entering the device, a liquid-supply 55 passage leading into said conduit near its receiving end, a valve arranged to permit liquid to enter said conduit through said passage and to prevent flow of fluids in the opposite direction, and an exhaust-receiving member positioned at the receiving end of said conduit and extending thereinto beyond said liquid-supply passage.

60 4. A device of the kind described having therein an exhaust-passage, an exhaust-conduit 65 extending longitudinally of said pas-

sage and arranged to receive a portion of pressure fluids entering the device, a liquid-supply passage leading into said conduit near its receiving end, a vacuum-chamber in communication with said liquid-supply 70 passage, a valve arranged to permit liquid to enter said conduit through said passage and to prevent flow of fluids in the opposite direction, and an exhaust-receiving member positioned at the receiving end of said conduit and extending thereinto beyond said liquid-supply passage.

5. A device of the kind described having therein an exhaust-passage, an exhaust-conduit 75 extending longitudinally of said passage and arranged to receive a portion of pressure fluids entering the device, a liquid-supply passage leading into said conduit near its receiving end, a valve arranged to permit liquid to enter said conduit through 80 said liquid-passage and to prevent flow of fluids in the opposite direction, and an exhaust-receiving member positioned at the receiving-end of said conduit and extending thereinto beyond said liquid-passage and being smaller at its discharge end than at its receiving end whereby there is a space between said member and conduit.

6. A device of the kind described having therein an exhaust-passage, an exhaust-conduit 85 extending longitudinally of said passage and arranged to receive a portion of pressure fluids entering the device, a liquid-supply passage leading into said conduit near its receiving end, a vacuum-chamber in 90 communication with said liquid-supply passage, a valve arranged to permit liquid to enter said conduit through said liquid-passage and to prevent flow of fluids in the opposite direction, and an exhaust-receiving member positioned at the receiving end of said conduit and extending thereinto beyond said liquid-passage and being smaller at its discharge end than at its receiving end whereby there is a space between said 95 member and conduit.

7. A device of the kind described having therein an exhaust-passage and a cooling-jacket therearound, a liquid-supply inlet for 100 said cooling-jacket, an exhaust-conduit extending longitudinally of said passage and arranged to receive a portion of pressure fluids entering the device, a liquid-supply 105 passage leading from said cooling-jacket into said conduit near its receiving end, and a valve arranged to permit liquid to enter said conduit through said liquid-passage and to close against flow of fluids in the opposite direction.

8. A device of the kind described having 110 therein an exhaust-passage and a cooling-jacket therearound, a liquid-supply inlet for 115 said cooling-jacket, an exhaust-conduit extending longitudinally of said passage and arranged to receive a portion of pressure 120 fluids entering the device, a liquid-supply 125 passage leading from said cooling-jacket into said conduit near its receiving end, and a valve arranged to permit liquid to enter said conduit through said liquid-passage and to close against flow of fluids in the opposite direction.

65 9. A device of the kind described having 130 therein an exhaust-passage and a cooling-jacket therearound, a liquid-supply inlet for said cooling-jacket, an exhaust-conduit extending longitudinally of said passage and arranged to receive a portion of pressure

fluids entering the device, a liquid-supply passage leading from said cooling-jacket into said conduit near its receiving end, a valve arranged to permit liquid to enter said conduit through said liquid passage and to close against flow of fluids in the opposite direction, and a vacuum-chamber in communication with said cooling-jacket.

9. A device of the kind described having 10 therein an exhaust-passage and a cooling-jacket therearound, a liquid-supply inlet for said cooling-jacket, an exhaust-conduit extending longitudinally of said passage and arranged to receive a portion of pressure 15 fluids entering the device, a liquid-supply passage leading from said cooling-jacket into said conduit near its receiving end, a valve arranged to permit liquid to enter said conduit through said liquid-supply passage and to close against flow of fluids in the opposite direction, and an exhaust-receiving member positioned at the receiving end of said conduit and extending thereinto 20 beyond said liquid-supply passage.

25 10. A device of the kind described having therein an exhaust-passage and a cooling-jacket therearound, a liquid-supply inlet for said cooling-jacket, an exhaust-conduit extending longitudinally of said passage and arranged to receive a portion of 30 exhaust fluids entering the device, a liquid-supply passage leading from said cooling-jacket into said conduit near its receiving end, a valve arranged to permit liquid to enter said conduit through said liquid-supply passage and to close against flow of fluids 35 in the opposite direction, an exhaust-receiving member positioned at the receiving end of said conduit and extending thereinto beyond said liquid-supply passage, and a 40 vacuum-chamber in communication with said cooling-jacket.

11. A device of the kind described having 45 therein an exhaust-passage, a liquid-supply conduit leading into said passage, a vacuum-chamber associated with said liquid-supply conduit, and a valve arranged to permit flow 50 of liquid from said conduit into said passage and to close against fluid flow in the opposite site direction in said conduit.

55 12. A device of the kind described having therein an exhaust-passage, an exhaust-conduit extending longitudinally of said passage and arranged to receive a portion of pressure fluids 60 entering the device, a liquid-supply passage leading into said conduit near its receiving end and said passage having a wall supporting said conduit, and a valve arranged to permit liquid to enter said conduit through said passage and to prevent fluid flow in the opposite direction in said conduit.

65 13. A device of the kind described having in combination an exhaust-passage provided with a valve closable in response to atmos-

pheric pressure, an exhaust-conduit extending longitudinally of said passage and arranged to receive a portion of pressure fluids entering the device, a liquid-supply passage leading into said conduit near its receiving end, and a valve arranged to permit liquid to enter said conduit through said liquid-supply passage and to prevent fluid flow in the opposite direction.

70 14. A device of the kind described having in combination an exhaust-passage provided with a valve closable in response to atmospheric pressure, an exhaust-conduit extending longitudinally of said passage and arranged to receive a portion of pressure fluids 75 entering the device, a liquid-supply passage leading into said conduit near its receiving end, a vacuum-chamber in communication with said liquid-supply passage, and a valve arranged to permit liquid to enter said conduit through said liquid-supply passage and to prevent fluid flow in the opposite direction.

80 15. A device of the kind described having in combination an exhaust-passage provided with a valve closable in response to atmospheric pressure, an exhaust-conduit extending longitudinally of said passage and arranged to receive a portion of pressure fluids 85 entering the device, a liquid-supply passage leading into said conduit near its receiving end, a valve arranged to permit liquid to enter said conduit through said liquid-supply passage and to prevent fluid flow in the opposite direction.

90 16. A device of the kind described having in combination an exhaust-passage provided with a valve closable in response to atmospheric pressure, an exhaust-conduit extending longitudinally of said passage and arranged to receive a portion of pressure fluids 95 entering the device, a liquid-supply passage leading into said conduit near its receiving end, a valve arranged to permit liquid to enter said conduit through said liquid-supply passage and to prevent fluid flow in the opposite direction, and an exhaust-receiving member positioned at the receiving end of 100 said conduit and extending thereinto beyond said liquid-supply passage.

105 17. A device of the kind described having in combination an exhaust-passage provided with a valve closable in response to atmospheric pressure, an exhaust-conduit extending longitudinally of said passage and arranged to receive a portion of pressure fluids 110 entering the device, a liquid-supply passage leading into said conduit near its receiving end, a vacuum-chamber in communication with said liquid-supply passage, a valve arranged to permit liquid to enter said conduit through said liquid-supply passage and to close against fluid flow in the opposite direction, 115 and an exhaust-receiving member positioned at the receiving end of said conduit and extending thereinto beyond said liquid-supply passage.

120 18. A device of the kind described having in combination an exhaust-passage provided with a valve closable in response to atmospheric pressure, an exhaust-conduit extending longitudinally of said passage and arranged to receive a portion of pressure fluids 125 entering the device, a liquid-supply passage leading into said conduit near its receiving end, a valve arranged to permit liquid to enter said conduit through said liquid-supply passage and to close against fluid flow in the opposite direction.

opposite direction, and an exhaust-receiving member positioned at the receiving end of said conduit and extending thereinto beyond said liquid-passage and being smaller 5 at its discharge end than at its receiving end whereby there is a space between said member and conduit.

18. A device of the kind described having in combination an exhaust-passage provided 10 with a valve closable in response to atmospheric pressure, an exhaust-conduit extending longitudinally of said passage and arranged to receive a portion of pressure fluids entering the device, a liquid-supply passage 15 leading into said conduit near its receiving end, a vacuum-chamber in communication with said liquid-passage, a valve arranged to permit liquid to enter said conduit through said liquid-passage and to close 20 against fluid flow in the opposite direction, and an exhaust-receiving member positioned at the receiving end of said conduit and extending thereinto beyond said liquid-passage and being smaller at its discharge end 25 that at its receiving end whereby there is a space between said member and conduit.

19. A device of the kind described having in combination an exhaust-passage provided with a valve closable in response to atmospheric 30 pressure, a cooling-jacket around said exhaust-passage, a liquid-inlet for said cooling-jacket, an exhaust-conduit extending longitudinally of said passage and arranged to receive a portion of pressure fluids entering the device, a liquid-passage leading from 35 said cooling-jacket into said conduit near its receiving end, and a valve arranged to permit liquid to enter said conduit through said liquid-passage and to close against fluid 40 flow in the opposite direction.

20. A device of the kind described having in combination an exhaust-passage provided with a valve closable in response to atmospheric pressure, a cooling-jacket 45 around said exhaust-passage, a liquid-inlet for said cooling-jacket, an exhaust-conduit extending longitudinally of said passage and arranged to receive a portion of pressure fluids entering the device, a liquid-passage leading from 50 said cooling-jacket into said conduit near its receiving end, a valve arranged to permit liquid to enter said conduit through said liquid-passage and to close against fluid flow in the opposite direction, 55 and a vacuum-chamber in communication with said cooling-jacket.

21. A device of the kind described having in combination an exhaust-passage provided with a valve closable in response 60 to atmospheric pressure, a cooling-jacket around said exhaust-passage, a liquid-inlet

for said cooling-jacket, an exhaust-conduit extending longitudinally of said passage and arranged to receive a portion of pressure fluids entering the device, a liquid-passage 65 leading from said cooling-jacket into said conduit near its receiving end, a valve arranged to permit liquid to enter said conduit through said liquid-passage and to close against fluid flow in the opposite direction, 70 and an exhaust-receiving member positioned at the receiving end of said conduit and extending thereinto beyond said liquid-passage.

22. A device of the kind described having in combination an exhaust-passage provided with a valve closable in response to atmospheric pressure, a cooling-jacket around said exhaust-passage, a liquid-inlet for said cooling-jacket, an exhaust-conduit 75 extending longitudinally of said passage and arranged to receive a portion of pressure fluids entering the device, a liquid-passage leading from said cooling-jacket to said conduit near its receiving end, a valve arranged to permit liquid to enter said conduit through said liquid-passage and to close against fluid flow in the opposite direction, an exhaust-receiving member positioned at the receiving end of said conduit 80 and extending thereinto beyond said liquid-passage, and a vacuum-chamber in communication with said cooling-jacket. 85

23. A device of the kind described having in combination an exhaust-passage provided with a valve closable in response to atmospheric pressure, a liquid-supply 95 conduit leading into said passage, a vacuum-chamber associated with said liquid-supply conduit, and a valve arranged to permit flow 100 of liquid from said conduit into said passage and to close against fluid flow in the opposite direction.

24. A device of the kind described having in combination an exhaust-passage provided 105 with a valve closable in response to atmospheric pressure, an exhaust-conduit extending longitudinally of said passage and arranged to receive a portion of pressure fluids entering the device, a liquid-supply passage 110 leading into said conduit near its receiving end and said liquid-passage having a wall supporting said conduit, and a valve arranged to permit liquid to enter said conduit through said liquid-passage and to close 115 against fluid flow in the opposite direction.

In testimony whereof, I affix my signature in the presence of two witnesses.

JOSEPH MARION KING.
